(57) **CLAIM**

The ornamental design for a latch mechanism for stroller, as shown and described.

DESCRIPTION

FIG. 1 is a perspective view of a latch mechanism for stroller showing our new design;

FIG. 2 is a right side elevational view thereof;

FIG. 3 is a top view thereof;

FIG. 4 is front view thereof;

FIG. 5 is a bottom view thereof;

FIG. 6 is a left side elevational view thereof;

FIG. 7 is a rear view thereof; and,

FIG. 8 is a reduced perspective view thereof, with the broken line showing for illustrative purposes only and forming no part of the claimed design.
